UNITED STATES PATENT OFFICE.

HENRY E. DEAVERS, OF LOS ANGELES, CALIFORNIA.

COMBINATION CUTTING AND ROLLING TOOL.

Application filed February 12, 1924. Serial No. 692,245.

To all whom it may concern:

Be it known that I, HENRY E. DEAVERS, a citizen of the United States, residing at Los Angeles, in the county of Los Angeles 5 and State of California, have invented new and useful Improvements in Combination Cutting and Rolling Tools, of which the following is a specification.

This improvement relates to improvements in a combination cutting tool and pipe straightener, more especially designed for cutting away metal drilling tools that have been broken off and lodged in the well in such a position that the drillers are 10 unable to recover or dislodge the same, and at the same time to effectually straighten accidentally deformed well casing.

It is the object of this invention to provide a combination tool in which the cutting or milling element may be readily changed from one form to another to suit varying conditions.

A further object of the invention is to provide a combination tool which may be conveniently utilized in cutting through broken metal drilling tools that may become wedged in a well and the well casing in order to continue the operations of well drilling at a different angle or inclination from that originally intended.

Further objects and advantages will be apparent from the following description, reference being had to the drawings accompanying the same in which;

35 Fig. 1 is a central vertical section through the lower end of an oil well with the casing in position illustrating the application of the improved tool.

Fig. 2 is a side elevation of the tool.

40 Fig. 3 is a central vertical section of the tool.

The combination cutting and pipe straightening tool herewith illustrated and described is designed for use in connection 45 with wells in which further drilling has been abandoned by reason of the lodgement of broken drilling tools, drill pipe, couplings, etc., which the drillers are unable to dislodge or recover. In such situations, 50 drillers oftentimes continue the drilling operations at a slightly different angle or inclination in order to avoid the obstructions in the well. By means of the improved tool, the drilling of an obstructed well can be 55 readily and quickly proceeded with, as the cutting end of the tool will effectually cut

away the metallic obstructions, and at the time the rollers will straighten out the deformed well casing, and thus enable the drillers to insert other well casing through 60 the original casing to encase the newly drilled portion of the well.

In the drawings hereto attached, the complete tool consists of a pipe straightening member 6, and a milling or cutting member 7 detachably secured to one another. The frame portion 8 of the straightening member, is provided with a centrally disposed bore 9 for the passage therethrough of mud laden water during the operation of the tool. 70 Formed integrally with the extreme upper end of the frame 8 is a threaded tapered pin 10 for the purpose of detachably securing the tool to the lower threaded end of a rotary drill pipe of usual construction. 75 The opposite end of the frame is also provided with a threaded taper pin 11 for detachably securing the cutting member 7 thereto. At the base of threaded pin 10 is formed a circular bearing flange 12 provided with a plurality of circularly arranged equally spaced bores 13 for the reception of the upper headed ends of a like number of roller bearing pins 14, each carrying a bearing roller 15, their upper ends 80 16 being of cylindrical form, while their lower ends 17 taper downwardly to their lower ends. The frame 8 directly below the bearing flange is cylindrical in form for approximately a third of its length, its remaining length being tapered downwardly and outwardly to the base of threaded pin 11, the taper being the same as the taper formed on the bearing rollers.

Cutting member 7 is provided in its top 85 wall with a tapered threaded socket 20 designed to engage the threaded pin 11 formed on the lower end of the frame to secure the straightening and cutting members together. The lower end of the cutting member is 90 provided with a centrally disposed cylindrical threaded cavity 21, which is engaged by a screw threaded plug 22 provided with a centrally disposed longitudinally extending bore 23 for the passage of mud laden water 100 therethrough, the outer end of plug end 22 being frusto-conical in configuration. Formed in the conical face of the plug are a plurality of radially disposed rabbeted tapered slots 24, equally spaced apart. Removably mounted in each slot are tapered cutting teeth 25 whose side walls engage the 105 110

rabbeted side walls of the slots 24, the longitudinally extending side edges 26 of the exposed portion of the cutting teeth 25 constitute the cutting edges.

- 5 The bottom wall of cutting member 7 is bevelled downwardly and outwardly from the periphery of the circular threaded cavity 21, and is provided with a plurality of radially disposed rabbeted tapered slots 27,
 10 in which are mounted cutting teeth 28, of the same general configuration as the cutting teeth 25 mounted on the conical face of plug 22. Threaded socket 20 and cavity 21 are connected by a bore 29 for the passage of
 15 the mud laden water from the bore 9 to the cutting tool. The top wall of the cutting member 7 is provided with a plurality of circularly arranged cylindrical recesses for the reception of the reduced lower ends of
 20 bearing pins 14.

In order to provide for any undue or unusual strain that might be imposed on the roller 17 during an operation of the device, I have provided downwardly extending lugs
 25 30, preferably formed integral with the flange 12 formed on the frame 6, the side faces of each lug being concaved longitudinally and of a depth to permit of the free rotation of the various rollers during the
 30 operation.

From this construction it will be apparent that should one of the roller pins become broken or bent during the operation of the device, the lugs 30 will tend to prevent
 35 a displacement of the rollers.

In operation the device is attached to the

lower end of a drill pipe which is rotated from the upper end of the well by a well known mechanism. Should a number of drill bits, couplings, and portions of drill 40 pipe become lodged in the well and the drillers are unable to proceed further into the well, the cutting member will mill the metal parts away or force the same to one side of the formation. Oftentimes the drillers in order to pass the obstructions in the 45 bottom of the well, have to drill a new hole, and drill at a different angle or inclination. In such cases the cutting tool is often forced through the well casing, the roller bearings 50 of the pipe straightener following up and straightening the edge of the drilled aperture in the casing so as to permit the passage therethrough of well casing of lesser diameter. 55

What I claim is:

In a device of the class described, comprising a frame member adapted for rotary movement, a plurality of pipe straightening rollers mounted in bearings formed in said 60 frame, the upper ends of said rollers being of cylindrical form and their lower ends conical, and a cutting tool secured to the frame below the rollers, whereby when the device is mounted in a deformed casing having 65 obstructions disposed therein it will operate to straighten the casing and to cut away the obstructions.

In witness that I claim the foregoing I have hereunto subscribed my name this 14th 70 day of January, 1924.

H. E. DEAVERS.
